UNITED STATES PATENT OFFICE.

LÉON REMBAUX, OF MOUSTIER SUR SAMBRE, BELGIUM.

TABLE FOR CASTING GLASS.

No. 879,491.

Specification of Letters Patent.

Patented Feb. 18, 1908.

Application filed October 25, 1906. Serial No. 340,572.

To all whom it may concern:

Be it known that I, LÉON REMBAUX, a subject of the King of Belgium, residing at 189 Rue de la Station, Moustier sur Sambre, in 5 the Kingdom of Belgium, constructional engineer, have invented certain new and useful Improvements in or Connected with Tables for Casting Glass, of which the following is a specification, reference being had to 10 the accompanying drawings and to the figures and letters marked thereon.

At the present time the casting of glass is performed upon rectangular and moving or 15 rolling casting tables which are generally composed of several parts of suitable thickness assembled and fastened together by the aid of bolts and keys. The thickness of these tables is relatively considerable and provided to resist the effects of the heat produced by contact with the melted glass and 20 to be sufficiently strong to support the weight of the expanding roller. Notwithstanding this thickness, after having run several casts of glass, the temperature of the table is 25 rapidly raised (to about 80° or 90° centigrade) and this rise of temperature produces a very considerable expansion of the upper surface of the table with relation to the lower part with the result that the table is 30 formed and bulges upward principally in a transverse direction. The convexity thus produced gives rise to a very serious inconvenience; the spreading leveling or flattening roller bears with considerable pressure 35 upon the table and the glass becomes of unequal thickness, thinner in the middle producing a manufacture having great disadvantages in the other phases of the making up of glass articles. Furthermore glass 40 badly cooled in the annealing oven is frequently broken, gives rise to much waste in cutting up, creates difficulty in obtaining large dimensions, increases the work and at the same time produces a new increase in the 45 waste in the operation of polishing. Attempts have been made to partly remedy this inconvenience by making the spreading or leveling roller slightly concave but this produces at the commencement of work the 50 opposite fault that is to say the first casts of glass are, by this arrangement, thicker in the middle than at the edges and when the temperature of the roller rises the effect of its curvature disappears little by little while 55 the table also commences its expansion bring-

ing back the inverse inconveniences. It is easy to realize the advantages which would accrue from a table remaining quite plane and in which the heat produces a minimum of deformation during the progress of the 60 work. These different considerations have given rise to the present invention and caused the construction of a practical device consisting of a casting table interiorly cooled by a continuous and multiple circulation of 65 water which is hereinafter described and represented in the drawings hereunto annexed in which:—

Figure 1 is a side elevation partly in section, the section being taken on the line A—B 70 of Fig. 2 of the casting table. Fig. 2 is a plan thereof partly in section the section being taken on the line C D of Fig. 1. Fig. 3 is a sectional end elevation the section being taken on the line E F G H I J of Fig. 2. 75

The table proper is composed of a series of parts or sections *a* preferably formed of cast iron and these sections are rectangular in cross section and are provided with open sided channels *b* cast with the sections for 80 the passage of bolts *c* and assembling keys *d* by which means no part of the table lies out of contact with the water. The lower wall or bottom carries pipes *e* for the passage of water and manholes *f* for cleaning and all the 85 sections *a* are formed with two compartments separated by a partition *g*. The series of sections are connected by bent tubes *h* which establish interior communication in such manner as to bring the water from the 90 center of the table in several currents toward the edges by a series of circuits into the different compartments.

A glance at the accompanying drawings will enable the course of the water in the interior of the table to be easily understood. In order to assure the distribution of the water a water reservoir *i* is arranged beneath the table together with a centrifugal high pressure pump *j* acted directly upon by an 100 electric motor *k*. The pump *j* takes the water to the bottom of the reservoir *i* at *l* and returns it by the conduit *m* whence the water can be distributed by the intermediary of two sluices or valves *n* the tubes *o* of 105 which are joined to the central sections *a* of the table. The water arriving at a pressure of 1½ atmospheres penetrates by the unions *p* into the interior of the table, circulates into the sections being diverted from the center 110

toward the exterior by the middle sections *a*, then returns to the center by the neighboring sections *a* across the unions *h* and *e* and thus in such manner that it at last finds an exit 5 under a pressure slightly lower to that of its admission by four spring valves *g*. The water in this manner carries off the heat from the center of the table toward the sides by spreading or distributing it toward the 10 neighboring sections *a* a number of times during the cast. It follows that the heat is distributed in a uniform manner among all the sections and that the exterior or side sections preserve approximately the same temperature 15 as those of the center always penetrating more rapidly into the bottom of the table which prevents the deformation thereof by transverse bulging leaving the latter quite plane during the work of casting. The 20 temperature of the circulation water may rise from 20° to 65° without inconvenience. According to whether the casting is to be done from the right or left side of the table it will be possible to render the introduction of the 25 water stronger on one side than the other by the aid of the sluices or valves *n*. The working of the circulation is done simply with regularity and great facility and the problem consisting in removing and distributing rationally 30 the heat imparted by the melted glass, is realized.

The table is mounted upon a double truck having eight wheels *r* which are mounted upon ball bearings so as to give the minimum of resistance in rotation. 35 The casting table thus constructed possesses or produces the advantages below enumerated.

1. Regularity in the thickness of the glass.
2. The spreading of the glass upon a table 40 having a uniformly distributed heat.
3. The obtaining of a greater useful surface with the same quantity of glass.
4. Facility for putting the sheet into the oven the glass adhering less to the table.
- 45 5. The cooling of the glass with a minimum of breakages.

Consequences:—

6. Greater production.
7. The diminution of the time of raising to the polishing stage. 50
8. Diminution in the waste of glass in this operation.
9. Perfect planimetry as well as diminished weight.
10. Possibility of constructing larger tables. 55
11. Facility for traveling of the latter.
12. Resulting from these different advantages considerable economy in raw materials and in manufacture.

Having now particularly described and ascertained the nature of the said invention and in what manner the same is to be performed I declare that what I claim is:—

1. The combination with a table for casting glass and having internal cooling passages, of a reservoir carried by the table and connected to the cooling passages and means on the table to cause the water to circulate from the reservoir through the passages and back into the reservoir. 65
2. The combination with a table for casting glass and having internal water-cooling passages, of a reservoir, a pump and a motor, all carried by the table, said pump and reservoir included in the water circuit, 75 whereby the motor will drive the pump to draw water from the reservoir and force it through the table.
3. The combination with a table for casting glass and having internal water cooling 80 passages, of a reservoir, a centrifugal pump and an electrical motor directly connected to the pump, all secured to and beneath the table, said pump and reservoir connected to the cooling passages to form therewith a continuous circuit. 85

In witness whereof I have hereunto set my hand in the presence of two witnesses.

LÉON REMBAUX.
